Primary Examiner — Brett Miller(74) *Attorney, Agent, or Firm* — Honigman LLP(57) **CLAIM**

I claim the ornamental design for a mold, as shown and described.

DESCRIPTION

FIG. 1 is a perspective view of a mold in accordance with my new design;

FIG. 2 is a top plan view of the mold of FIG. 1;

FIG. 3 is a front elevation view of the mold of FIG. 1;

FIG. 4 is a side elevation view of the mold of FIG. 1, an opposite side elevation view being identical;

FIG. 5 is a rear elevation view of the mold of FIG. 1; and,

FIG. 6 is a reflected bottom plan view of the mold of FIG. 1.

The broken lines shown throughout the drawing figures are portions of the mold that form no part of the claimed design.
